UNITED STATES PATENT OFFICE.

DONALD G. ACKERLY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed September 14, 1926. Serial No. 135,463.

My invention relates to railway traffic controlling apparatus, and particularly to apparatus of the type wherein traffic governing mechanism is controlled in accordance with coded or periodically interrupted current.

I will describe two forms of apparatus embodying my invention, and will then point out the novel features thereof in 10 claims.

In the accompanying drawing, Fig. 1 is a diagrammatic view showing one form of apparatus embodying my invention, and Fig. 2 is a chart showing the relative lengths 15 of periodic current supply to give two different indications. Fig. 3 is a view showing a modification of the apparatus shown in Fig. 1 and also embodying my invention.

Similar reference characters refer to similar parts in each of the views.

Referring first to Fig. 1, the reference character A designates a main relay which is periodically energized for relatively long intervals or for relatively short intervals, according to the indication which it is desired 25 that the apparatus shall give. As shown in Fig. 2, energization of this relay for relatively long intervals will cause a proceed indication to be given, whereas energization of this relay for relatively short intervals will cause a caution indication to be given. Relay A is quick acting in both pick up and release, so that the contacts of this relay follow 30 very closely the application and interruption of current in the relay winding.

The reference character P designates a pole-changing relay which has both slow release and slow pick up characteristics. When relay A is closed, relay P is energized 40 by virtue of a circuit which will be obvious from the drawing, and if relay A is operating in response to the proceed code, then each time that contact 1 is closed relay P will be energized for a period long enough to cause this relay to close. On the other hand, if relay A is operating in response to the caution code, then each time that contact 1 is closed relay P will be energized but not for a period long enough to cause this relay to close. 45 Owing to the slow release characteristic of relay P, when this relay is closed, due to the

proceed code, it remains closed during the intervals between the impulses forming that code.

The reference character C designates a 55 slow-release relay, which relay, however, picks up quickly upon the application of current to its winding. This relay is controlled by a contact 4 in relay A, which contact is closed momentarily while relay A is closing 60 and also while it is opening, but which contact is open while the relay is closed and also while it is open. Relay C will, therefore, be energized each time relay A closes or opens during either the proceed or the caution code, and owing to the slow-release characteristic 65 of relay C, it will remain closed during the intervals between impulses in either code.

The reference character D designates a 70 polarized relay which is controlled jointly by relays A, P and C. When relay D is energized in normal direction, it lights a proceed lamp G, when energized in reverse direction it lights a caution lamp Y, and when de-energized it lights a stop lamp R. The circuits 75 for these lamps are obvious from the drawing. The characteristics of relay D are such that it will close its normal or reverse contact promptly when energized, but will hold such contact closed during the intervals between impulses in either code.

I will first assume that relay A is operating in response to the proceed code. Relays P and C are both closed, so that relay D is energized by a circuit which passes from terminal B of a suitable source of current, through front contact 2 of relay A, front contact 5 of relay P, winding of relay D, front contact 8 of relay C, front contact 6 of relay P, and front contact 3 of relay A to terminal O of the same source of current. Relay D is then energized in the normal direction so that the proceed lamp G is lighted. Assuming now that relay A is operating in response to the caution code, relay C is closed but relay P is open, because this relay cannot pick up during the relatively short periods of energization of relay A. The circuit for relay D is then from terminal B, through front contact 2 of relay A, back contact 5 of relay P, contact 8 of relay C, winding of relay D, back contact 7 of relay

P, and front contact 3 of relay A to terminal O. Relay D is therefore energized in the reverse direction, so that the caution lamp Y is lighted. If relay A is continuously de-
5 energized, relay C is open, so that the circuit for relay D is open, and, consequently, the stop lamp R is lighted. If relay A is continuously energized, relay C is open, so that the circuit for relay D is open and the stop
10 lamp R is lighted.

Referring now to Fig. 3, the apparatus shown in this view is the same as that shown in Fig. 1, in so far as the control of the pole-changing relay P is concerned, but the slow-
15 releasing relay C has been omitted and the function of the latter relay is accomplished by two contacts 10 and 11 in relay A. Each of these contacts is closed while relay A is closing and also while relay A is opening,
20 but each is open when relay A is fully closed and also when it is fully opened. The circuit for the polarized relay D is from terminal B, through contact 10 of relay A, contact 5 of relay P, winding of relay D, contact 6 of relay P, and contact 11 of relay A.

The operation of the apparatus shown in Fig. 3, is as follows: When relay A is operating in response to the proceed code, relay P is closed, and each time that relay A
30 closes or opens, relay D will be momentarily energized in the normal direction so that the proceed lamp G is lighted. When relay A is operating in response to the caution code, however, relay P will be open, so that relay D will be energized in the reverse direction with the result that the caution lamp Y will be lighted. It is, of course, understood that, as in Fig. 1, relay D is so designed that it will hold its
35 normal or its reverse contact closed during the intervals between impulses in either code.

Although I have herein shown and described only two forms of apparatus embodying my invention, it is understood that
40 various changes and modifications may be made therein within the scope of the appended claims without departing from the spirit and scope of my invention.

Having thus described my invention, what
50 I claim is:

1. Railway traffic controlling apparatus comprising a main relay periodically closed for relatively short or relatively long intervals, a pole-changing relay energized while said main relay is closed but arranged to close only when the main relay is closed for relatively long intervals, a polarized relay, means operating when said main relay is closed to energize said polarized relay in one direction or the other according as said pole-changing relay is open or closed, and traffic

governing mechanism controlled by said polarized relay.

2. Railway traffic controlling apparatus comprising a main relay periodically closed for relatively short or relatively long intervals, a pole changing relay energized while said main relay is closed but arranged to close only when the main relay is closed for relatively long intervals, a polarized relay, a slow release relay energized while said main relay is closing or opening but de-energized while the main relay is open or closed, means operating while said main relay and said slow release relay are both closed to energize said polarized relay in one direction or the other according as said pole changing relay is open or closed, and traffic governing mechanism controlled by said polarized relay.

3. Railway traffic controlling apparatus comprising a main relay periodically closed for relatively short or relatively long intervals, a pole-changing relay energized while said main relay is closed but arranged to close only when the main relay is closed for relatively long intervals, a slow release relay energized while said main relay is closing or opening but de-energized while the main relay is open or closed, and traffic governing mechanism controlled by the contacts of said pole-changing relay and by said slow release relay.

4. Railway traffic controlling apparatus comprising normally open contacts periodically closed for relatively short or relatively long intervals, a pole-changing relay energized while said contacts are closed but arranged to close only when the contacts are closed for relatively long intervals, a slow release relay energized while said contacts are closing or opening but not while said contacts are closed or open, and traffic governing mechanism controlled by said pole-changing relay and by said slow release relay.

5. Railway traffic controlling apparatus comprising a main relay periodically closed for relatively short or relatively long intervals, a pole changing relay energized while said main relay is closed but arranged to close only when the main relay is closed for relatively long intervals, a slow-releasing polarized relay, means operating while said main relay is closing and also while it is opening to energize said polarized relay in one direction or the other according as said pole-changing relay is open or closed, and traffic governing mechanism controlled by said polarized relay.

In testimony whereof I affix my signature.

DONALD G. ACKERLY.
